UNITED STATES PATENT OFFICE.

JULIEN P. FRIEZ, OF BALTIMORE, MARYLAND.

RECORDING WATER-GAGE.

SPECIFICATION forming part of Letters Patent No. 681,536, dated August 27, 1901.

Application filed August 25, 1900. Serial No. 28,035. (No model.)

To all whom it may concern:

Be it known that I, JULIEN P. FRIEZ, a resident of Baltimore, in the State of Maryland, have invented certain new and useful Improvements in Recording Water-Gages; and I do hereby declare the following to be a full, clear, and exact description of the invention, such as will enable others skilled in the art to which it pertains to make and use the same.

The invention relates to water-gages for measuring and recording variations in the depth of liquids either still or flowing, and particularly in the variation of the depth of the flowing contents of rivers, irrigating-ditches and sewers, reservoirs, and also of tide water.

Its objects are to increase the efficiency of such gages and to insure convenience and safety both in use and in transportation.

The invention consists in the construction herein described and pointed out.

In the accompanying drawings, Figure 1 is a perspective of the improved recording water-gage. Fig. 2 is a partial perspective of a cover therefor. Fig. 3 is an end elevation, the cover being denoted by broken lines. Fig. 4 is a perspective of a pen-stock carrier. Fig. 5 is a partial section showing the connection of the pen-stock with its carrier. Fig. 6 is a partial side elevation of the carrier and pen-stock. Fig. 7 is a perspective of a pen. Fig. 8 is a perspective of a detail of the pen-stock carrier. Fig. 9 is a longitudinal section of the gage, a clock-mechanism case being shown in full lines. Fig. 10 includes perspectives of the details of a spring-held bearing for a cylinder-journal. Fig. 11 includes perspectives of the bearing for the pen-stock-carrier screw-rod and its coacting guide-rod. Figs. 12 and 13 are respectively edge and side elevations of a pencil-holder and holder-carrier. Fig. 14 is a view showing a clutch to connect the recording-cylinder and one of its journals. Fig. 15 is a side elevation of a detail.

In general the instrument comprises clock mechanism, a pen or pencil regularly moved by the clock, and a record-sheet supported on a cylinder rotatably moved about its axis in either direction by a counterbalanced float.

Numerals 1 denotes a base, and 2 the clock-case.

3 denotes a screw-threaded rod having journals in a post 4 and in the clock-case and uniformly rotated by any suitable mechanism in the case, being in the present case driven by a gear 2^X, meshing with a gear 3^X, fixed on the rod.

5 denotes a pen, 6 a pen-stock, and 7 a pen-stock carrier. The pen-stock carrier comprises a part 8, preferably tubular, having a loose or sliding connection with rod 3. It also has a like connection with a guide-rod 9. Between ears 10, fixed to the sliding part of the carrier, is pivoted a section 11, suitably threaded to engage the threads of the rotating screw-rod 3. The threaded carrier-section 11 is held to its work by a spring 12, connecting a stud 13 on the section with a stud 14 on the extension 15, forming part of the carrier 8. The threaded section 11 of the carrier can be disengaged from rod 3 by depressing the arm 16, whereupon the pen-stock carrier can be freely moved lengthwise the rod for resetting or other purposes.

16^X denotes an interval in the threads of rod 3 to provide for the automatic arrest of the movement of the carrier lengthwise the rod by breaking its operative connection with said rod, and thus mediate breaking its connection with the clockwork. This interval is a little longer than the screw-threaded portion of the section 11, (see Figs. 8, 6, and 4,) which section comprises the sole thread connection of the carrier and rod, so that when said section is adjacent the interval the parts are not operatively connected and the carrier rests, though the motor continues to run. This avoids injury to the apparatus, which would otherwise occur if the observer failed to stop or reset the devices before the motor forced the tube 8 of the carrier against part 4.

Since the operative connection of section 11 and rod 3 can be broken at will by depressing the arm 16, thereby turning section 11 about its pivot 11^X, the construction provides for the convenient and easy adjustment of the pen-carrier lengthwise the cylinder, and since devices to be described provide for the adjustment of the cylinder and record-sheet circumferentially the record can be made to start from any desired point on the sheet as required under various conditions.

It has heretofore been proposed to continu-

ously rotate a cylinder and intermittently move lengthwise the same by means of a float and weight. My improvement contemplates an operation continued without inspection 5 for a definite period and then automatically arrested, as is desirable in case the instrument is not inspected or reset at the termination of said period. As the pen is continuously moved until it is arrested, injury might 10 and would result were no means provided for disconnecting it from its motor. It is incidental to the improved construction that the diameter of the recording-cylinder and of its case may be considerably reduced without 15 diminishing the capacity of the instrument.

The pen-stock is supported on a vertical part or post 17 of the carrier extension 15 by means of a disk 18, connected thereto by a screw 19. A three-armed spring having a 20 central hole 20 to receive the screw 19 is held on a stud 21 of the disk and bears on the head of the post. By these means the pen-stock is held yieldingly in a vertical plane. 23 denotes a similar connection between a 25 disk 25 of the pen-stock and a horizontal disk 24, fixed to disk 18. This provides for a horizontal adjustment of the pen-stock, which is held in a yielding manner upon the disk 24.

The rods 3 and 9, with the pen-stock carrier, 30 can be detached from the machine by removing the screw 25^x, which holds the bar 26 upon the top of the post 4, whereupon the rods can be withdrawn from their bearing in the clock-case and also from the carrier, the 35 rods being loosely supported in the clock-case for that purpose. The parts are assembled by a reverse operation.

In Figs. 12 and 13 is shown a pencil holder and carrier which may be substituted for the 40 pen-stock and carrier when desired. The holder 27 is pivotally supported on a carrier-post 28 between suitable ears.

29 denotes a spring to hold the pencil to its work, and 30 is a nut to adjust the tension of 45 the spring.

The cylinder 31, which carries the record-sheet 32, is moved back and forth by a counterbalanced float 33 to carry the sheet under the pen constantly moved parallel to its axis. 50 The axis of this cylinder has bearings in a part fixed to the clock-case and in posts 34 and 35.

36 denotes a float-counterbalancing weight, and 37 a perforated metal band having one 55 end secured to the float and the other to the weight. The band is operatively connected to a sprocket-wheel 38, having pins 39, suitably engaging holes 40 in the band. Cords and driving-pulleys are objectionable, for the 60 reason that the cords expand and contract with variations of moisture and sprocket-chains are rendered inexact by wear if not so made at first. Said sprocket-wheel has its shaft 43 journaled in small bracket posts or 65 studs 41 and in the intermediate post 35. This provision against contraction and ex-

pansion of the driving connection and against slip is especially important in an apparatus requiring accurate work and exposed to moisture. Power is transmitted by means of a 70 pinion 42 on shaft 43 of the wheel 38. Said pinion drives a spur gear-wheel 44, fixed on the shaft 45.

46 denotes a larger sprocket-wheel, which may be used instead of the wheel 38, if required. As represented in this case, its diameter equals that of the cylinder, but it may be given any desired diameter. 75

47 denotes slots in the base for the free passage of the perforated band which operatively 80 connects the float, weight, and wheel.

48 denotes pulleys employed to spread and guide the band when the small sprocket-wheel is used. To enable said wheel to be easily disconnected from the gear-wheel 44, 85 the shaft is supported to slide endwise in its bearings to throw the pinion 42 out of mesh with the wheel 44. A pivoted stop to hold said sliding shaft when adjusted is denoted by 49. 90

49^x indicates a spring to hold the stop engaged in a groove 48^x when pinion 42 is slid out of mesh with wheel 44. Said groove is indicated at the left of Fig. 9. In said figure the stop 49 is shown covering the end of shaft 95 43 and holding pinion 42 engaged with gear 44.

The shaft 45 is detachably connected to the cylinder 31 by transverse arms having pins 51, adapted to engage holes 52 in a disk 53. This disk has a screw-threaded stud 55, and the 100 disk is held against the cylinder-head by a nut screwing on the inner end of the stud within the cylinder. This nut holds an armed spring 54 adjustably against the inner face of the cylinder-head, the spring-arms bearing 105 on said head, and the whole providing a detachable connection between the cylinder and the shaft 45.

56 is a spring to hold the pins 51 of the shaft-arms 45^x engaged with suitable holes in the 110 disk 53, and 57 is a screw-stop whereby the pressure of the spring can be varied and limited. This constitutes an efficient and easily-manipulated spring-held clutch. The pins can be disengaged from the openings and 115 moved away from the disk 53 and from the cylinder 31, to which the disk is connected, by overcoming said spring 56. When thus disengaged, the shaft 45 can be turned until one of its arms having a pin 51 is engaged 120 under the head of a screw 57, as shown in Fig. 14. The cylinder 31 can then be readily detached for substituting a new record-sheet or for other purposes. The construction permits the cylinder to be initially adjusted to 125 bring the record-sheet in suitable relation to the pen. To render the cylinder easy of application to or detachment from the clock-case, an open journal-bearing 58 is provided with flaring guides 59. 130

60 denotes rubber bands to hold the record-sheet on the cylinder. Metallic holders here-

tofore employed have proved inconvenient and unnecessarily expensive and those extending lengthwise the cylinder obstruct the pen. Rubber bands avoid these objections and are specially advantageous in application and operation.

5 61 denotes a milled disk for adjusting the cylinder.

62 is a socket to receive a key for the clock 10 mechanism and is placed on the face of the clock-case next the cylinder.

63 denotes a glazed inspection-opening in the case.

64 is a short post to receive the sprocket- 15 band for transportation or when not in use. The band is coiled in a receiver 65, which is placed on the post.

66 denotes a screw fixed to the post and passing freely through the top of the receiver. 20 The weight 36 has a screw-threaded socket to engage said screw and hold the band-receiver upon the base and also secure said weight thereto.

67 denotes a cover detachably hinged to the 25 base, which is provided with a cover-seat 68 and with loops 69 in the seat to receive the hooks 70, fixed to the cover. Opposite this hinge connection is a hook 71, held in a keeper 72 by a spring-pin 73. The cover-seat is be- 30 low and exterior to the upper surface of the base to exclude rain, wind, or dust.

74 denotes a pocket in the cover to receive the float, and 75 is a pivoted spring to hold the float in the pocket.

35 In practice the float having been suitably connected to one of the sprocket-wheels and counterbalanced will be suspended in a well or bay situated in the liquid whose height variations are to be recorded to protect it 40 from the action of waves, tides, or winds.

The instrument having been suitably arranged and the clock wound to run, preferably for a week at least, the pen (or pencil) will be continuously moved along its support- 45 ing-rod and the paper transversely moved under the pen by the counterbalanced float, actuated by changes in the liquid-level, such changes being recorded on a suitably-graduated sheet.

50 I am aware that an automatically-reversible pen-stock carrier has been operatively supported upon two parallel screws combined with a guide-bar, one of said screws being positively and the other meditately driven by

55 an incased motor. In such construction the positively-driven screw had a bevel-gear or pinion situated on its end outside a screw-rod bearing and on its opposite end a gear-wheel also outside a screw-rod bearing, whereby the

60 ready removal of the screw is prevented. In my construction the screw 3 has a readily-detachable bearing in the motor-case beyond its gear 3^X and the guide-rod 9 has its proximate end detachably connected to the motor-case, the opposite ends being held in the bearings by a detachable bar.

Having thus described my invention, what

I claim as new, and desire to secure by Letters Patent, is—

1. In a recording water-gage comprising a cylinder actuated by a float, a plurality of power-transmitting wheels of different sizes and having different shafts and adapted to be operatively connected in alternation with the float, one of said wheels being adapted to be moved to a situation of rest when the other is in operation, and an adjustable stop for the movable wheel to hold it either in or out of operative connection.

2. In a recording water-gage, a base, a cylinder supported above the base, a float suspended below the base, a counterbalancing-weight, a plurality of intermediate cylinder-driving wheels of different sizes and separately operative, a power-transmitting connection, and pulleys in the base adjacent one of the wheels to guide said connection, said base being slotted for shifting the connection without separating it from the float.

3. In a recording water-gage, a slotted base, a cylinder supported above the base, a float suspended below the base, a counterbalancing-weight, a plurality of intermediate cylinder-driving wheels of different sizes and separately operative, a power-transmitting connection attached to the float and weight, and pulleys in the base-slots adjacent one of the wheels to guide said connection and to permit the connection to be moved from one driving-wheel to another without separation from the float or weight, the inner proximate edges of such slots being situated in planes tangential to one of the wheels.

4. In a recording water-gage, the combination of a pen, a detachable cylinder supporting a record-sheet, devices for moving the pen in contact with and lengthwise the cylinder, a driving-shaft, a clutch comprising a member carried by said shaft to connect the shaft and cylinder, a movable coacting clutch 110 member bearing on the cylinder-head, and a spring for each member, one of the springs 54 being situated within the cylinder and holding the last-named clutch to the cylinder-head, all substantially as set forth, whereby 115 the cylinder can be readily detached, or whereby the cylinder and sheet can be adjusted circumferentially.

5. In a recording water-gage, a cylinder carrying a record-sheet, a pen-stock carrier, a 120 guide-rod for the carrier, a screw for moving the carrier lengthwise the cylinder, a pen-stock carrier extension, a pen-stock, a disk 18 provided with studs arranged transversely to each other, springs on the studs, and screws 125 engaged with the studs to hold the springs one upon the pen-stock and the other upon the carrier extension.

6. In a recording water-gage, the cylinder carrying a record-sheet, the screw-threaded rod, the guide-rod, the pen-stock carrier having an arm 15 freely movable on the guide-rod, the carrier-post 17, the pen-stock mounted on the post, and mechanism for moving the

carrier on the rods comprising the swinging arm 16 carrying an open screw-threaded section 11.

7. In a recording water-gage, the cylinder carrying a record-sheet, the screw-threaded rod, the guide-rod, the pen-stock carrier having an arm 15 freely movable on the guide-rod, the carrier-post 17, the pen-stock mounted on the post, mechanism for moving the carrier on the rods comprising the swinging arm 16 carrying an open screw-threaded section 11, said arm being pivoted in the carrier, and the spring to hold the section engaged with the screw-threaded rod.

15 8. In a recording water-gage, a movable pen-carrier, a motor for uniformly moving the carrier in one direction, a carrier supporting and moving screw, a float, a rotatable cylinder, and power-transmitting connections, all substantially as described, whereby the cylinder is turned by the movements of the float, said screw being situated beside the

cylinder and having its thread omitted at 16^x at a point immediately opposite the cylinder near its end for automatically disconnecting 25 the carrier from its motor at a predetermined time and bringing said carrier to a state of rest without the arrest of the motor.

9. In a recording water-gage, a float, a cylinder rotated by the float, a movable pen-carrier, a motor for uniformly moving the carrier in one direction, power-transmitting connections between the motor and the carrier, and a device to automatically disconnect the carrier from its motor at a predetermined time to bring said carrier to a state of rest without the arrest of said motor.

In testimony whereof I have signed this specification in the presence of two subscribing witnesses.

JULIEN P. FRIEZ.
